CORKSCREW WITH POINT PROTECTOR

Gaspar Ippolito, New York, N. Y.

Application March 21, 1945, Serial No. 583,932

1 Claim. (Cl. 81—3.45)

1

This invention relates to new and useful improvements in an all purpose opener.

More particularly, the invention proposes the construction of an opener as mentioned which is characterized by a rigid sheet metal member having a screw-driver portion at one end, a bottle cap opener and can puncturer portion at the other end, and a central cutout portion for a corkscrew at the center. It is proposed to extend a corkscrew across said central cutout portion and to pivotally mount said corkscrew on the material of said member to one side of said central cutout portion.

It is proposed that said corkscrew have a wire base portion which includes a coil against one face of said member and which continues into a strand passing through said member, and said strand continuing into a side section extending along the other face of said member.

The all purpose opener can be used to remove bottle caps, to puncture the tops of tin cans, to remove corks from bottles and also may be used as a screw-driver. The screw-driver end will open cans having a flat top cover over them. It can also be used to pry loose thumb tacks.

The invention also contemplates a simple arrangement by which the corkscrew may be held in the folded condition in which its pointed end is shielded.

Still further, it is proposed to construct the opener as described, which essentially consists of two parts only.

For further comprehension of the invention, and of the objects and advantages thereof, reference will be had to the following description and accompanying drawings, and the appended claim in which the various novel features of the invention are more particularly set forth.

In the accompanying drawing, forming a material part of this disclosure:

Fig. 1 is a perspective view of an opener constructed in accordance with this invention.

Fig. 2 is a fragmentary elevational view looking in the direction of the arrows from line 2—2 of Fig. 1.

Fig. 3 is a vertical sectional view taken on the line 3—3 of Fig. 2.

Fig. 4 is an elevational view of an all-purpose opener constructed in accordance with a modified form of this invention.

Fig. 5 is a sectional view taken on the line 5—5 of Fig. 4.

The all purpose opener, in accordance with that form of the invention disclosed in Figs. 1 to 3, includes a rigid sheet-metal member 10 having a

2

screw-driver portion 11 at one end and a bottle-cap opener and can puncturer portion 12 at the other end. The rigid sheet metal member 10 has a central cut-out portion 13 for a corkscrew. A corkscrew 14 extends across said central cutout portion 13 and is pivotally mounted on the material of said member to one side of said central cutout portion 14. Said corkscrew 14 has a wire base portion which includes a curl portion 15 disposed against one face of said member 10, said curl portion 15 continuing into a strand 16 passing through said member 10 and said strand 16 continuing into a side portion 17 extending along the other face of said member 10.

15 The corkscrew 14 has its outer edge 18 pointed in the usual way. It is formed from curl wire material. The member 10 has a notch 19 by which it may be engaged over the edge of some part that is to be bent or broken.

20 In Figs. 4 and 5 a modified form of the invention has been disclosed in which the corkscrew 14 has the strand portion 16 passing through an elongated opening 20 in member 10. A leaf spring 21 engages against the strand portion 16, normally urging the corkscrew 14 forwards. The remote edge of the central cutout 13 is formed with a split edge portion 22, forming a pocket for receiving the pointed end 18 of the corkscrew 14.

25 The manner of using this form of the invention follows:

The resilient spring 21 tends to urge the corkscrew 14 into a position in which its pointed end will be retained within the pocket formed by the split edge portion 22 to retain the corkscrew in an inoperative position. To release the pointed end 18 of the corkscrew 14, to free it to be moved to an operative position, it is merely necessary to apply pressure to the corkscrew 14 in a longitudinal direction against the action of the spring

30 21, to withdraw the pointed end 18 from the pocket formed by the split-edges portion 22 to free the corkscrew 14 to be pivoted to a right angular operative position relative to the rigid sheet-metal member 10. To return the corkscrew 40 to its inoperative position, the above procedure is reversed.

35 In other respects this form of the invention is similar to that previously shown and like reference numerals identify like parts in each of the 45 several views.

40 While I have illustrated and described the preferred embodiments of my invention, it is to be understood that I do not limit myself to the precise constructions herein disclosed and the right 50 is reserved to all changes and modifications com-

ing within the scope of the invention as defined in the appended claim.

Having thus described my invention, what I claim as new, and desire to secure by United States Letters Patent is:

An all purpose opener, comprising a shank having on one end an L-shaped arm providing a finger hold and an offset lug located forwardly of said arm, a spiral corkscrew having an offset trunnion in its rear end pivotally engaged with said offset lug, a wire member having an arm which engages the shank of the spiral corkscrew and a loop which bears against the side of the offset lug, a flat spring secured to said offset lug to engage said wire loop, and a lug extending lateral of the first-named shank and provided with a pocket to receive the point of the corkscrew, whereby said corkscrew point will be normally guarded when the said corkscrew is in folded position on the shank, the L-shaped arm

5 providing means for holding the first-named shank when the corkscrew is operated.

GASPER IPPOLITO.
